METAL DETECTOR

Robert F. Gardiner, 4729 N. 7th Ave.,
Phoenix, Ariz. 85013

Filed Apr. 7, 1971, Ser. No. 132,251

Term of patent 14 years

Int. Cl. D10—05
U.S. Cl. D52—6

FIG. 1 is a right front perspective view of a metal detector showing my new design; and

FIG. 2 is a left rear perspective view, on an enlarged scale, of the upper portion of FIG. 1, the lower section having been omitted for ease of illustration.

I claim:

The ornamental design for a metal detector, as shown and described.
